DESIGN FOR A BOTTLE

Clarence K. Simon, New York, N. Y., assignor to Dominion Distilleries Inc., Jersey City, N. J., a corporation of New Jersey

Application January 13, 1934, Serial No. 50,398

Term of patent 14 years

To all whom it may concern:

Be it known that I, CLARENCE K. SIMON, a citizen of the United States of America, and residing in the Borough of Manhattan, city and State of New York, have invented a new, original, and ornamental Design for Bottles, of which the following is a specification, reference being had to the accompanying drawing, forming part thereof.

Fig. 1 is a front view of a bottle, showing my new design;

Fig. 2 is a back view of the same.

Fig. 3 is a top view of such bottle.

I claim:

The ornamental design for a bottle, as shown.

CLARENCE K. SIMON.
